UNITED STATES PATENT OFFICE.

GEORGE S. WITHAM, JR., OF HUDSON FALLS, NEW YORK

PAPER-MAKING MACHINE.

Application filed May 24, 1926. Serial No. 111,407.

This invention relates to paper making machines, and more particularly to the wet end of a paper making machine including the head box, slices, etc., or that end where the liquid stock is delivered to the web-forming or Fourdrinier wire part of the machine.

It has heretofore been proposed to provide an opening in the front wall of the head box for delivery of the liquid stock 10 therein to the web-forming or Fourdrinier wire part of the machine, and to employ a metallic apron board adjacent said opening and over which the liquid stock is delivered to said web-forming part. It has further 15 been proposed to provide a high pond and a high sectional slice over the apron board in order to maintain the necessary head of liquid stock flowing to the Fourdrinier wire, particularly at high speeds thereof. Constructions such as above referred to, however, have certain defects and disadvantages in that the high pond and the high sectional slice involve additional expense in their installation, necessitate the use of showers at 20 the pond, and produce a tendency toward cross currents of the liquid stock and bulking of the stock on the web-forming or Fourdrinier wire part of the machine.

The principal objects of this invention are 25 to provide a construction for the wet end of a paper making machine, which eliminates the defects and disadvantages above referred to; which avoids formation of cross currents in the liquid stock by the employment of adjustable gates or baffles in the head box for controlling the flow of stock therethrough; which utilizes a pond or quiet storage space in the head box to maintain the desired head 30 of stock for high speeds of the wire; which automatically removes any foam or froth 35 formed in the head box before said foam can reach the wire to cause breaks or the like in the sheet; which insures an efficient delivery 40 of the liquid stock to the wire, through the medium of a nozzle and slice constructed as a unit and adjustably mounted on the front 45 of the head box; which affords an apron board forming the bottom wall of the nozzle and adjustable vertically in accordance with 50 like adjustments of the nozzle; which, through the medium of a one-piece slice and hydraulic means on the nozzle, avoids bulking 55 of the stock on the wire; and which is an efficient, expeditious, and inexpensive construction for the wet end of a paper making 60 machine.

In order the more clearly to understand this invention reference may be had to the accompanying drawing which illustrates one embodiment of the inventive idea and 60 wherein—

Fig. 1 is a longitudinal sectional view showing one embodiment of the invention installed with a Fourdrinier paper making machine; and

Fig. 2 is a transverse sectional view on the line 2—2 of Fig. 1.

Referring to the drawing, wherein like reference numerals designate like parts throughout the several views, 5 indicates a 70 head box and 6 the web-forming or Fourdrinier wire part of the machine receiving the liquid stock from the head box. The wire 6 passes over the usual breast roll 7 and said wire and roll are mounted in the usual 75 manner forwardly of the head box 5. The head box has a rear wall 8, front wall 9, side walls 10, 10 and bottom wall 11, and the front wall 9 is provided with an opening 12 through which the liquid stock is delivered 80 to the wire 6.

In accordance with the present invention, the head box 5 is divided into a plurality of communicating compartments, and the flow of the liquid stock through said compartments is controlled by adjustable gates or baffles to prevent the formation of cross currents and bulking of the stock on the web-forming part of the machine. The communicating compartments and the adjustable 90 baffles may be constructed in any suitable manner, but as herein shown the head box is preferably provided with a plurality of baffles 13, 14 and 15 which extend transversely of the head box across the entire 95 width thereof and divide said head box into a plurality of communicating compartments 16, 17, 18 and 19. The liquid stock is delivered into the head box by the usual screens (not shown) and the adjustable baffles for controlling the flow of liquid stock through the compartments 16, 17, 18 and 19, are indicated at 20 and 21.

The adjustable gates or baffles 20 and 21 extend across the openings 22 and 23 between the compartments 16 and 17 and 18 and 19 respectively, and said baffles are supported on rock shafts 24 and 25 journaled at 26 and 27 on the head box and each provided with a hand crank 28 or other suitable 105 means for moving the baffles in either direction to vary the size of the openings 22 and 110 23.

- 23 and control the flow of liquid stock there-through. For supporting the baffles 20 and 21 on the rock shafts 24 and 25, the latter are preferably provided with crank arms 29 and 30 carrying at their free ends rods 31 and 32, the lower ends of which are riveted or otherwise suitably secured at 33 and 34 to the baffles 20 and 21. The upper ends of the rods 31 and 32 are threaded at 35 and 36 and extend freely through suitable openings in cross pieces 37 and 38 pivotally mounted at 39 and 40 on the free ends of the cranks 29 and 30. The threaded ends 35 and 36 of the rods 31 and 32 are provided with nuts 41 and 42 which rotatably engage the upper surfaces of the cross pieces 37 and 38 respectively, and serve as means for adjusting the baffles 20 and 21 independently of the rock shafts 24 and 25.
- 20 The bottom of the head box is preferably provided with curved fillets 43 and 44 which eliminate dead corners in the several compartments of the head box and, in accordance with the present invention, the head box 25 is provided with a compartment serving as a quiet storage space at the front of the head box to maintain the desired head of pressure of the stock for high speeds of the wire. This storage space is preferably constituted by the compartment 19, the walls of which extend upwardly to the top of the head box so that the level of the liquid stock in said compartment may be maintained at a considerable height above the wire 6. The 30 compartment 19 thus serves to maintain the desired head of stock above the wire, particularly for high speeds thereof, and together with a nozzle and slice to be hereinafter described, avoids the necessity for a high pond and high slices forwardly of the head box. The compartment 19 is preferably provided at the top thereof with means for removing any foam or froth formed in the head box from the surface of the liquid stock in 35 said compartment. This foam removing means is preferably comprised by a header 45 extending transversely across the compartment 19 over the liquid stock therein and provided with a plurality of branches, one 40 of which is indicated at 46. The header 45 is supplied with white or fresh water under pressure from any suitable source and the branches of said header are each provided therein with openings located so as to direct 45 sprays of water therethrough into the compartment at an angle, thus removing any foam or froth on the surface of the liquid stock toward the rear of the machine.
- The foam or froth removed rearwardly by 50 the sprays is directed over a float or skimming plate 47 disposed adjacent an opening 48, through which the foam or froth passes to any suitable means for collecting and carrying off the same. The opening 48 is 55 preferably located in the head box wall 10 at the rear of the machine and the skimming plate 47 is mounted for vertical adjustment adjacent said opening, whereby the float or skimming plate may be positioned on the surface of the liquid stock regardless of the level thereof in the compartment 19. Any suitable means may be provided for adjusting the skimming plate vertically but as herein shown, said means preferably comprises a rod 49, the lower end of which is anchored on the skimming plate in any desired manner. The upper end of said rod is threaded at 50 and extends freely through a suitable opening in a plate 51 fastened on the upper edge of the head box over the opening 48. A nut 52 threaded on the upper end of the rod 49, rotatably engages the upper surface of the plate 51 and serves, when rotated, to raise or lower the float or skimming plate 47 in accordance with the direction of rotation of said nut. In order to prevent overflow of the liquid stock through the opening 48 when the level of the stock is to be maintained above the bottom of said opening, the skimming plate has secured thereto a gate 53 which is slidably mounted on the wall of the compartment 19 in guides 54, 54 disposed adjacent the side margins of the opening 48. It will thus appear that the level of the liquid stock may be changed in the compartment to vary the head above the wire 6 and that any desired level of the stock above the bottom of the opening can be maintained by vertical adjustment of the gate and skimming plate through the medium of the rod 49 and nut 52. For the purpose of diffusing the liquid stock and delivering the same at all angles to the wire 6, a perforated board 55 is provided. Said board is preferably disposed at an angle across the opening 12 of the head box and removably mounted in guides 56, 56 secured to the head box walls 10, 10 adjacent the ends of the opening 12.
- In accordance with the present invention the liquid stock flows from the head box 110 storage space to the web-forming part of the machine through a structure mounted for vertical adjustment on the front of the head box, and said structure comprises a nozzle and apron board formed as a unit, a one-piece slice for maintaining uniformity of thickness across the entire width of the sheet, devices for adjusting the slice, and hydraulic means for levelling the sheet and reducing the work of the slice. The unitary structure above referred to may be constructed in any suitable manner but as herein shown the nozzle of said structure is provided by side walls 57, 57, a top wall 58 inclined downwardly and forwardly from the head box, and a bottom wall 59 which forms the apron over which the liquid stock is delivered from the storage space 19 to wire 6. The walls 58 and 59 of the nozzle have secured or formed thereon gates or 115

- vertical apron portions 60 and 61 respectively, which are slidably engaged in guides 62, 62 secured to the front wall of the head box adjacent the ends of the opening 12. The opening 12, as clearly shown in Fig. 1, is made considerably larger than the nozzle opening, to provide communication between the nozzle and the head box when the nozzle is adjusted vertically, and the gates or apron portions 60 and 61 thus serve to confine the flow of stock from the head box through the nozzle in the various adjusted positions of the latter. The nozzle is preferably reinforced by brackets 63, 63 disposed under the apron board 59, and for the purpose of supporting the nozzle and adjusting the same vertically in accordance with like adjustment of the wire 6, the brackets 63, 63 are provided with screws 64, 64 or other desired fastening means extending through suitable openings in the brackets and gate 61 and removably secured in the front wall 9 of the head box.
- The one-piece slice carried by the adjustable nozzle, is indicated at 65 and said slice is slidably guided over the discharge opening of the nozzle in guides 66, 66 on each of the nozzle walls 47, 47. Mounted on each end of the slice is a stationary nut or threaded boss 67, and hand screws threaded through each nut or boss and rotatably engaging the upper surfaces of the machine top rails 67', 67' serve to raise or lower the slice. One of these hand screws is indicated at 68 and each of the same is provided with a hand wheel 69 for rotating the screw in either direction to raise or lower the slice and thus regulate the flow of stock from the nozzle to the wire 6. This one-piece slice avoids bulking of the sheet occurring when sectional slices are employed and thus insures that the stock on the wire 6 will be of uniform thickness across the entire width thereof. Each of the slice hand screws is provided with a pointer 70 which, when the slice is stationary or being adjusted, cooperates with a scale 71 mounted on the adjacent nozzle wall 47 and serves to indicate accurately and quickly the size of the discharge opening of the nozzle. A secondary one-piece slice 72 may be provided, if so desired, and said slice is slidably mounted at each end in guides 73, 73 on the adjacent framework 74 of the deckle equipment. A pair of screws, one of which is indicated at 75, serve to adjust the slice 71 vertically and each of said hand screws is threaded in a suitable opening formed in a bracket 71' fixed on the end of the slice. The lower end of the hand screw rotatably engages in a socket 71" on one of the top rails 67', 67' and a hand wheel 76 fixed on the upper end of each hand screw 75, serves to turn the same and thus raise or lower the slice in accordance with the direction of rotation of the hand wheel.
- The slice 72 is provided at each end with a pointer 77 cooperating with a scale 78 on the adjacent deckle framework 74 and serving to indicate the size of the opening between the wire 6 and the lower edge of the slice 72.
- The hydraulic levelling means carried by the nozzle, is preferably stationary and slidably fitted therein to provide for vertical adjustment of the nozzle. Said levelling means may be of any suitable construction but as herein shown the same preferably comprises a header 79 extending transversely of the machine over the nozzle and connected with a pipe 80 leading from any suitable source of white or fresh water under pressure. The header 77 is provided at spaced intervals along the same with branch pipes 81, 81 which extend downwardly into the nozzle and are slidably fitted in openings 82, 82 formed in the nozzle wall 58. The header 79 is of sufficient diameter to obtain the desired head of pressure on the water which may be delivered through the pipes 81, 81 into the nozzle to dilute the liquid stock at any desired point or points therein. The flow of water through the pipes 81, 81 is controlled by valves 83, 83, one in each pipe, and if, for example, it is found upon adjustment of the slice or slices, that the stock is running a little heavy at any point or points across the width of the wire, one or more of the valves 83, 83 in line with said point or points may be opened so that water flowing through the corresponding pipe or pipes 83, 83 into the nozzle will dilute the liquid stock, thus levelling the same on the wire 6 and assisting the slice to maintain a sheet of uniform thickness across the entire width of the wire.
- It will appear from the foregoing that by the present invention the necessity for a high pond and a high slice or slices forwardly of the head box is avoided, and that through the medium of the adjustable baffles 20, 21 and the high storage space 19 in the head box, the flow of liquid stock is controlled as desired and the head of stock maintained at the proper height for high speeds of the web-forming or Fourdrinier wire part 6 of the machine. Moreover, the one-piece adjustable slice or slices and the hydraulic levelling means serve to produce a sheet of uniform thickness across the entire width thereof and the mounting of the nozzle and devices carried thereby provides a unitary structure which can be adjusted vertically as desired without having to disconnect and disassemble the parts. The accompanying drawing illustrates the embodiment of this invention described above with more or less particularity but it is to be expressly understood that the drawing is for purposes of illustration only and that this invention may be embodied in a variety of mechanical

expressions within the scope of the appended claims.

What is claimed is:—

1. In a paper-making machine, the combination with the web-forming part, of a head-box for the liquid stock and having an opening in the front wall thereof, a nozzle, apron and slice adjustably mounted as a unit on said wall over the opening therein, and a compartment in the head-box communicating with the latter and the nozzle, said compartment having walls extending upwardly above the nozzle and slice to provide a pond or storage space in which the level of the liquid stock may be maintained above the nozzle, slice, and web-forming part.
2. In a paper-making machine, the combination with the web-forming part, of a head-box for the liquid stock provided with an opening substantially aligned with the web-forming part, and a nozzle and a slice arranged as a unit adjacent the opening and adjustably supported on the head-box.
3. In a paper-making machine, the combination with the web-forming part, of a head-box for the liquid stock extending above the web-forming part and having an opening substantially aligned therewith, and a nozzle, apron, and one-piece slice arranged as a unit and adjustably mounted on the head-box adjacent said opening and the web-forming part.
4. In a paper-making machine, the combination with the web-forming part, of a head-box for the liquid stock having an opening substantially aligned with the web-forming part, a nozzle adjustably mounted on the head-box over said opening and adapted to deliver the liquid stock to said web-forming part, and a one-piece slice mounted on the nozzle for adjustment across the delivering opening thereof.
5. In a paper-making machine, the combination with the web-forming part, of a head-box for the liquid stock provided with an opening substantially aligned with the web-forming part, a nozzle for delivering liquid stock from the head-box to the web-forming

part through the opening and having an area less than that of the opening, guide means on the head-box adjacent the opening, and means on the nozzle supporting the same on the guide means and adapted to close part of said opening.

6. In a paper-making machine, a head-box provided in the front wall thereof with an opening, and a nozzle, apron, and slice constructed as a unit and adjustably mounted on the head-box adjacent said opening.

7. In a paper-making machine, a head-box provided in the front wall thereof with an opening, a nozzle communicating with the head-box through said opening and having a bottom wall forming an apron board, and means providing an adjustable mounting for the nozzle and apron board on the head-box.

8. In a paper-making machine, a head-box provided in its front wall with an opening, a nozzle communicating with the head-box through said opening and having a bottom wall forming an apron board, a one-piece slice mounted on the nozzle for adjustment across its delivery opening, and means providing an adjustable mounting for the nozzle on the head-box.

9. In a paper-making machine, a head-box provided in its front wall with an opening, guide means adjacent the margin of said opening, and a nozzle, apron, and an adjustable one-piece slice constructed as a unit slidably mounted on the guide means over said opening.

10. In a paper-making machine, a head-box provided in its front wall with an opening, guides on the head-box adjacent opposite ends of the opening, a nozzle communicating with the head-box through the opening and having a bottom wall portion forming an apron board, and gates or aprons on the nozzle engaging said guides and adjustably secured on the front wall of the head-box.

In testimony whereof I have signed this specification.

GEORGE S. WITHAM, Jr.
